GAME APPARATUS

John Michael Fusco, Altoona, Pa.

Application March 22, 1937, Serial No. 132,428

1 Claim. (Cl. 273—142)

The invention relates to a game apparatus and more especially to a baseball game device.

The primary object of the invention is the provision of an apparatus or device of this character, wherein the acts simulating those of the offensive and defensive teams in the playing of a real national game of baseball will be indicated for the counting against both the batting and fielding activities of opponents in this game.

10 Another object of the invention is the provision of an apparatus or device of this character, wherein the entertainment, excitement and amusement incident to the playing of the real national game of baseball will be present and in 15 this manner lending attractiveness to the participants operating such apparatus or device.

A further object of the invention is the provision of an apparatus or device of this character, wherein the playing of the real national game of baseball can be reproduced in all of its refinements, technique and skill incident thereto through the use of such apparatus or device, the 20 scoring and the activities of the playing elements being readily registered and the winning of 25 the said game discerned.

A still further object of the invention is the provision of an apparatus or device of this character, wherein executed plays by opponents throughout the innings of the game of baseball 30 can be registered and the winning score obtainable.

A still further object of the invention is the provision of an apparatus or device of this character, which is simple in its construction, thoroughly reliable and effective in operation, novel 35 in its make-up, neat and attractive in appearance, affording pleasure and amusement to the users thereof and inexpensive to manufacture.

With these and other objects in view, the invention consists in the features of construction, combination and arrangement of parts as will be hereinafter more fully described, illustrated in the accompanying drawing, which discloses the preferred embodiment of the invention and 40 pointed out in the claim hereunto appended.

45 In the accompanying drawing:

Figure 1 is a plan view of the apparatus or device constructed in accordance with the invention.

50 Figure 2 is a fragmentary enlarged sectional view taken on the line 2—2 of Figure 1.

Figure 3 is a perspective view of one of the scoring or registering elements employed with the apparatus or device.

55 Figure 4 is a perspective view of one of the

playing pieces used with the apparatus or device.

Similar reference characters indicate corresponding parts throughout the several views in the drawing.

5 Referring to the drawing in detail, A designates generally a body structure formed with an upper playing bed 10 which is elevated with respect to a base or bottom 11, the bed on its outer or exposed surface has provided thereon a 10 playing field involving a diamond 12 including a pitcher's zone 13, a catcher's zone 14, first base 15, second base 16, third base 17, short stop 18, center field 19 and right and left fields 20 and 21, respectively, as well as a batting station 22. 15 These zones 13 to 21 are formed with circular openings 23 through which are exposed freely turnable spherical members 24, they being slightly protruded through the openings 23 and each contacts with a turn table 25 fitted upon a turning staff or stem 26 perpendicularly arranged and rotatably journaled at 27 and 28, respectively, in said body, the staff or stem being protruded above the bed 10 and at the upper end has formed therewith a hand knob 29. When 25 the staff or stem 26 is rotated manually at the knob 29 through manual spinning activity, the spherical members 24 will be caused to rotate. These members 24 carry indicia at 30 indicative of each and all of executed plays by those players 30 of offensive and defensive teams in the playing of the real national game of baseball and thus such executed play or plays will be indicated at the zones in the playing field.

The batting station 22 has provided in the 35 bed 10 a window or opening 31 for exposing a dial 32 therethrough, this dial being rotatably supported upon a staff or stem 33 perpendicularly journaled similarly to each staff or stem 26 and terminating at its upper end in a hand knob 34 40 for manual turning of said dial. The dial 32 at its upper face exposed through the window 31 carries suitable indicia at 35 indicative of hits, strikes, balls and outs for scoring by a batting team. 45

The bed 10 adjacent to the catcher's zone 14 has provided thereon a scoring panel 36 formed with a central space 37 and divided outer spaces 38 and 39, respectively. The spaces 38 have arranged therein sockets 40, each for accommodating a counting pin or plug 41. Similarly the spaces 39 have the sockets 42, each for a counting pin 41. Rotatably fitting the space 37 and suitably journaled in the bed 10 are counting disks or registering dials 43, each provided 55

with numerals ranging consecutively and of the required digits as at 44 for coaction with indicator marks 45 for identifying strikes, balls and outs, the scoring of a batter. The spaces 38 are subdivided into two groups, one for visitors and the other for local teams and carry indicia, respectively, "Runs", "Hits" and "Errors" so that by the use of pins or plugs scorings similar thereto can be registered while the spaces 39 bear title "Innings" whereby there can be registered the innings played in the game of baseball in the use of the apparatus or device.

By the members 24 and the dial 32, the acts of the respective players on each batting and fielding team will be indicated and scoring of these made by the pins or plugs 41 and the disks or dials 43 thus enabling the playing by innings of an imitative game of the real national game of baseball with its technic, entertainment and amusement incident thereto. The runs scored by each team, the safeties, errors, strikes, balls and outs occurring being discernible and scoring of each team and the winner of the game obtainable.

25 The disks or dials 43 are provided with hand knobs 46 for convenience in the turning thereof for scoring or registering purposes in their coaction with the indicators 45.

30 The zones 14, 15, 16 and 17 have provided therein sockets 47 for accommodating the marking pins or plugs 41. Each spherical member 24 is properly marked corresponding to executed plays of a game involving offensive and defense-

sive teams, for example, the national game of American baseball, and for an instance in this game the pitcher on the mound throws the ball to the batter and the dial 32 after operation thereof indicates that the ball thrown is a 5 strike, a foul or a hit ball, while the spherical member 24 at the pitcher's mound identifies the activity on the part of this player and such dial will disclose the directional course of the ball, that is to say, whether it has been carried to 10 infield or outfields. Assuming that the indication is that the ball has been hit to the right field. Now the member 24 within the zone of the right field when actuated will indicate whether the hit ball is good for two bases, home 15 run or three bases or may be indicative of a fly-out at right field and in this manner the plays and activities of both teams in the playing of the game will be identified by both the members 24 and dial 32, respectively, for scores 20 by both teams and the winning of the game by either from the beginning to the end of the game.

What is claimed is:

In a game apparatus, a support having playing field indicia thereon and provided with an opening, a spherical member exposed through said opening and having indicia indicative of playing activity, a turntable arranged at the opening and supporting the spherical member 30 for rotation thereof, and means for imparting rotation to said turntable.

JOHN MICHAEL FUSCO.
